UNITED STATES PATENT OFFICE.

JOHN C. BARCLAY, OF NEW YORK, N. Y.

PERFORATING-MACHINE.

No. 893,419.

Specification of Letters Patent.

Patented July 14, 1908.

Application filed October 13, 1906. Serial No. 338,851.

To all whom it may concern:

Be it known that I, JOHN C. BARCLAY, a citizen of the United States, residing at New York, in the county of New York and State 5 of New York, have invented certain new and useful Improvements in Perforating-Machines; and I do hereby declare the following to be a full, clear, and exact description of the same, such as will enable others skilled in the art to which it appertains to make and 10 use the same:

My invention relates to improvements in perforating machines, and more particularly to machines of the class employed for perforating or otherwise marking paper strips or 15 ribbons, such for example as those used in the Wheatstone automatic telegraph system and various other automatic and printing telegraph systems. My invention is not 20 limited in its application to the perforating of telegraph strips and I may use it for any purpose for which marking or perforating machines or mechanism such as described are adapted.

25 The perforating machine herein illustrated and described is a key-board machine having character keys and levers arranged as in typewriting machines.

The objects of my invention are to improve 30 and simplify marking and perforating machines such as are employed in telegraph systems; to make such machines more rapid in action, to improve the "touch" and general working qualities of such machines, so 35 that they may be operated without excessive labor on the part of the operator even at high speed; to improve and simplify the marking or punching mechanism, selecting mechanism, and paper feed mechanism, and other 40 sub-mechanisms of machines of this class; to make the connection between the various key levers and the corresponding punching and spacing devices very direct; and generally to make the machine compact, relatively 45 simple, relatively inexpensive to make, and comparatively noiseless in operation.

The machine illustrated in the accompanying drawings is adapted for perforating paper strips or ribbons for the Wheatstone and 50 similar automatic telegraph systems. It may punch said strips according to any desired code, the selecting mechanism being arranged to cause the strip to be fed the proper distance, and to cause the proper 55 arrangement of holes to be punched, for each

particular character of the code selected. The mechanism of this machine comprises (a) punching mechanism; (b) paper feed mechanism; (c) key-board comprising finger keys and selecting means operated thereby 60 and controlling appropriate devices of the punching and paper feed mechanisms, whereby at each operation of a finger key, the proper combination is "set up" to punch this character in the strip, and by which 65 space determining means are operated to regulate the feeding of the paper strip to correspond with the space occupied by each character so punched; (d) power mechanism, independent of but controlled by the keys, 70 whereby the actual work of feeding the paper and of punching is performed by a motor, preferably a continuously running motor.

I will now proceed to describe my invention with reference to the accompanying 75 drawings, in which one form of perforating machine embodying my invention is illustrated, and will then point out the novel features in claims.

In the said drawings: Figure 1 shows a top 80 view of my said perforating machine, a portion of the cover of the box containing the paper reel, being broken away; Fig. 2 shows a front elevation of the said machine—parts much in rear of the front being omitted for 85 the sake of clearness of illustration; Fig. 3 is a detail side view of one of the key levers, illustrating the selecting devices carried thereby and engaging the tension wires which control the punching and paper feed 90 mechanisms; Fig. 4 shows a top view of the machine with the key-board and associated parts removed, the punching and paper feed mechanisms being sectioned on the line $x-x$ of Fig. 2; Fig. 5 is a detail side view of the 95 contact device controlling the restoring magnet of the paper feed mechanism; Fig. 6 shows a face view of the friction clutch or yielding drive through which the paper feed mechanism is driven, and Fig. 6^a shows a 100 transverse section of such yielding friction drive device; Fig. 7 shows a section from front to rear of the machine, showing especially the punching and paper feed mechanisms and operating devices; Fig. 8 is a detail 105 rear view of the mechanism for restoring the stop pins of the paper feed mechanism; Fig. 9 shows a portion of the paper strip with one character punched thereon; Fig. 10 shows a detail horizontal section of the mechanism 110

for keeping the paper strip under tension; Fig. 11 shows an elevation of the machine taken from the right of Fig. 1; Fig. 12 is a detail side view of the principal portion of 5 the paper feed and spacing mechanism; Fig. 12^a is a top view of the same; Fig. 13 shows in detail one of the pivoted levers operated by tension wires, by which the pushers which set up the stop pins by which the length of 10 feed is determined, are operated; Fig. 14 shows a detail elevation and partial section of the punching mechanism on a scale larger than that of Fig. 2; Fig. 15 shows a top view of the transmission mechanism by which the 15 cam shaft of the punching mechanism and the driving shaft of the paper feed mechanism, are driven; Fig. 16 shows a detail elevation of the parts shown in Fig. 15; Fig. 16^a shows a detail top view of the clutch which 20 drives the punching mechanism; Fig. 17 shows a detail section from front to rear of the punching and paper feed mechanisms; Fig. 17^a shows a detail section through the punching head; and Figs. 18-23 inclusive 25 are detail views illustrating the arrangement of the punches and associated parts, Fig. 18 showing a top view of all the punches, Fig. 19 a top view with the upper row of punches removed, Fig. 20 a top view with both the top 30 and the middle row of punches removed, Fig. 21 showing a section on the line 21-21 of Fig. 18, Fig. 22 showing a section on the line 22-22 of Fig. 18, and Fig. 23 showing a transverse section on the line 23-23 of 35 Fig. 18.

In said drawings, 1 designates generally a key-board, 2 designates generally a punching mechanism, 3 designates generally paper feed and spacing mechanism, 4 designates a driving motor, and 5 designates generally transmission mechanism. The key-board comprises finger keys 6 and corresponding key levers 7, each operating, through selecting devices hereinafter described, certain of two 40 series of tension wires, 8 and 9, located beneath the key-board. Each wire 8, when depressed by a key-lever, effects the operation of a corresponding punch. Each wire 9, when depressed by a finger key, effects the 45 adjustment of a stop pin of the paper feed and spacing mechanism, whereby the distance the paper strip is to be fed is regulated. For depressing the appropriate tension wires of series 8 and 9, each key lever is provided 50 with one or more forks 10 (Figs. 3 and 7) located over the particular wires of series 8 which that lever is to operate, and is further provided with a similar fork 11 located over the particular wire of series 9 which that lever 55 is to operate. Beneath the key-levers, and extending transversely across the key-board, is a universal bar 12 carried by arms 13 mounted upon a shaft 14, and this universal bar is normally held upward by springs 15 (see Figs. 1 and 7). When any one of the

finger keys is depressed and this universal bar 12 is depressed, rotating shaft 14, means hereinafter described closes a clutch whereby motor 4 is caused to communicate motion to the punching mechanism; the restoring arm 70 of the paper feed and spacing mechanism being likewise set. The finger keys have returning springs 16 (Figs. 3 and 7). The universal bar 12, when returned by its spring 15, causes an arm 17 (Fig. 5) mounted on shaft 75 14 to close contact between its contact spring 18 and adjustable contact screw 19, thereby closing the circuit of the restoring magnet of the paper feed mechanism.

The paper strip 21 passes from a reel 20, 80 around suitable guide rollers 22 and between tension rollers 23 and 24, through the punching mechanism 2, around the feed wheel of the paper feed mechanism 3, and thence through a paper guide 25 to the left hand side 85 of the machine. The front of this guide being open (see Fig. 2) the punched strip passes in complete view of the operator, who can thus read it at any time and so be advised of mistakes in punching.

Punching mechanism. (See particularly Figs. 1, 2, 11, 14, 17 and 17^a.)—The punching mechanism comprises a plurality of punches arranged in three horizontal series, 26, 27 and 28, located one above another, 90 and slidably mounted in a punch frame 29, in front of which is a die plate 30. The paper strip 21 passes through a slot between the front of frame 29 and said die plate. The middle row of punches, 27, punch in the 100 paper strip, (see Fig. 9) a series of small holes designed to be engaged by the feed wheel of Wheatstone and similar automatic transmitters. These holes therefore form no part of the particular character punched, but are 105 merely required for convenience in feeding the paper strip through the perforating machine and through said transmitter. It is preferable that said middle row of holes be punched at the time that the holes making 110 up the character to be marked on said strips are punched, so as to insure exact correspondence between those holes which determine the characters, and the holes which determine the feeding of the paper strip. Hence 115 the employment of three series of punches in this machine. To actuate these punches, two series of fingers, 31 and 32, are provided; series 31 being arranged in front of series 32 and to be driven forward thereby. Each 120 such finger 31 or 32, is mounted upon a separate bell crank 33, to which is connected a corresponding tension wire of series 8. Springs 34 tend to hold bell cranks 33 up, in the position shown in Fig. 14. Each finger 125 31 of the front series, has a head 35 adapted to actuate the opposite punch of the lower series 28, said head being above such punch, and therefore out of operative position with respect thereto, at all times, except when the 130

corresponding bell crank 33 carrying that finger is depressed; depression of any one of the bell cranks 33 which carry the front series of fingers 31, having the effect of moving the 5 corresponding finger down so that its head 35 is opposite the corresponding punch of series 28. Each finger 32 of the rear series has, in like manner, a head 36 adapted to actuate a corresponding punch of the upper 10 series 26, but normally out of line with such punch, and adapted to be drawn into line therewith by depression of the corresponding bell crank 33; which bell crank will be depressed when the corresponding tension 15 wire of series 8 is actuated; and each of these rear fingers 32 is further provided with a second head 37 adapted to actuate that finger of series 31 which is directly in front. A universal bar 38 carried by pivoted arms 39 20 and normally held backward by a spring 40, returns both series of fingers. A driving arm 41 pivoted at 42 and actuated by a cam 43 on a shaft 44, drives forward all of said fingers each time said cam rotates; but 25 although all of the fingers are thus driven forward, only those fingers actuate punches which have been depressed by their tension wires and so brought into line with their respective punches. It will be seen, therefore, 30 that by proper selection of tension wires 8, any desired combination of upper and lower punches, or any punch or punches of either series, may be selected and operated.

The punches of series 28 are provided with 35 lugs 45 (Figs. 17^a-23 incl.) projecting up between the corresponding punches of series 27 and each engaging a lug 46 of the middle-row punch immediately above it and also a corresponding lug 46 of the punch 27 next beyond. The punches of the upper series, 26, 40 each carry a lug 48 engaging a lug 46^a of the punches 27 beneath. The middle-row punches are arranged in pairs, (with one additional punch to the right, in Figs. 18-22 45 incl.) the left-hand punch of each such pair (as viewed in Figs. 18-22 incl.) having a lug 46^a secured to it, the right-hand punch of such pair passing freely through a hole in such lug 46^a, but having itself a lug 46^b, 50 which said lug 46^a engages. The construction is such that when any punch 26 moves forward, its lug 48 engages the lug 46^a of the pair of middle-row punches beneath, lug 46^a in turn engaging lug 46^b, and both of said 55 middle-row punches being carried forward; and that when any punch 28 moves forward, its lug 45, engaging the lug 46 of the punch 27 above and engaging also the lug 46 of the punch 27 next beyond, moves both forward. 60 The punches are caused to operate in this manner, to correspond with the conditions of the telegraphic code according to which the holes are to be punched, space being required between the perforations.

65 To return the several punches, after the

driver 41 and fingers 31 and 32 have been retracted, springs are provided. The several punches 27 of the middle row have each its individual return spring, 47. For returning the upper-row punches, 26, I provide a pivoted universal bar, 49, engaging all of the lugs 48 of the upper-row punches, and having a bell-crank extension 50, to which is connected a spring 51. For returning the lower-row punches, 28, I provide same with 70 lugs 52, like lugs 48 but projecting downward, and engaging a universal bar 53 actuated by a returning spring 54.

Cam shaft 44 by which the driver 41 is operated, revolves intermittently, being 80 driven from the motor 4 through a clutch 55 (Figs. 1, 11 and 15). Said clutch comprises two jaw members, one, 56, driven by gear wheel 57 from the main driving shaft or armature shaft of the motor; the other jaw 85 member, 58, being mounted to slide on shaft 44 and having a spring 58^a tending to press it into engagement with member 56. A stop 59 (Figs. 1, 15 and 16) pivoted at 60, (Figs. 15 and 16) normally engages a lug 62 carried 90 by this clutch member 58, and both prevents rotation of said clutch member 58 and holds it out of engagement with clutch member 56. But when universal bar 12 is depressed upon the depression of a finger key, and causes 95 shaft 14 to rotate, an arm 63 on said shaft operating through rod 64, moves downward a trip 65 (Fig. 16), mounted to move vertically as shown in said figure, thus freeing stop 60 from lug 62, and permitting clutch 100 member 58 to be forced by spring 58^a into engagement with clutch member 56, thereby causing shaft 44 to revolve. As trip 65 moves downward, a lug 66 engaging its cam surface 67, forces said trip to the left of Fig. 105 16 against the pressure of spring 68 on rod 64, so that said trip is caused to release the stop 59, which is at once pulled down by its spring 61 in position to engage lug 62 again upon the completion of one revolution of 110 shaft 44. In the path of rotation of lug 62 is a spiral throw-out cam 69, which, near the conclusion of one revolution of the lug 62, engages the same and forces it gradually away from clutch member 56, thus opening 115 the clutch, and at the conclusion of one revolution lug 62 jumps from the end of the cam 69 into engagement with stop 59, and is thereby held. The construction of the parts is such, it will be seen, that for each depression of a finger key only one revolution of 120 cam shaft 44 can occur.

Clutch member 58 is mounted to slide upon the shaft 44, but is not directly keyed thereto. Instead, a disk 70 forming a backing for 125 spring 58^a is secured to shaft 44, and clutch member 58 has a projection 71 (Fig. 15) passing through a hole in said disk 70 and engaging a notch 72 in a collar 73 on shaft 44.

From the above, the construction and 130

operation of the punching mechanism, including the clutch mechanism through which the same is driven, will be understood.

Paper feed mechanism.—Some of the characters of the telegraphic code such as that with which my perforator arranged as shown is particularly intended to be used, occupy more space than others. It is therefore desirable to cause the paper to be fed, not the maximum distance each time, but only the distance required for the particular character just punched. To this end I employ a second series of tension wires, 9, and each finger key, when depressed, operates that tension wire of series 9 which corresponds to the space on the paper strip occupied by the corresponding character. There may be as many of these tension wires, each corresponding to a different length of feed of the paper strip, as desired. I have shown six such wires, which gives a sufficient number of different lengths of feed for the particular code which I prefer to employ. For other codes, as for example the ordinary Wheatstone code, I may provide more such wires and devices operated thereby.

The paper strip 21, after passing through the punching head 29, passes around a feed wheel 74 (Figs. 1, 11, 12 and 17) provided with teeth 75 adapted to enter the middle series of perforations in the paper strip 21, and so to insure uniform feeding of said paper strip by preventing slipping. This wheel carries a large number of stop pins 76, arranged in a circle near the periphery of the wheel, and adapted to slide vertically in said wheel. Each such pin is surrounded by a spiral spring 77, the only purpose of which is to act as a friction brake or drag thereon to hold said pin against gravity or vibration in any position in which the pin may be adjusted. Above wheel 74 is a plate 78 in which is a notch 79 (Fig. 12) of a width corresponding to, or greater than, the maximum length of feed required for any one character of the paper strip. Above this plate 78 there is, in turn, another plate 80 in which, and in the frame plate 81 above, there is a narrower notch 82 (Figs. 1 and 12) in registry with the end portion of notch 79. The feed drum or wheel 74 is arranged to be rotated intermittently by means to be described hereinafter, and prior to the beginning of such rotation, one of the stop pins 76 is moved upward by one of the six pushers 83 (Fig. 12), each corresponding to, and arranged to be operated by, a corresponding one of the series of tension wires 9, as hereinafter described, that particular pin 76 being pushed up, which will permit the wheel 74 to rotate the proper distance by the time the upper end of such pin 76 engages the limiting shoulder 84 of slot 79. When the pin so raised encounters said shoulder 84, the feed wheel 74 comes to rest. To restore the pins 76 to first

position I provide an arm 85 carried by a vertically slidable rod 86, but arranged also to rotate somewhat, and normally held to the right of Figs. 8 and 12^a by a spring 87. The end of this arm 85 just clears shoulder 84, as shown in Fig. 12^a, but engages any pin 76 which has been elevated; such pin, when brought to rest by shoulder 84, being half in engagement with said shoulder, and half in engagement with arm 85.

I have previously explained that when any one of the finger keys 6 is depressed, the clutch 54 which drives shaft 44 is closed and said shaft begins to rotate. Shaft 44 carries a cam 88 arranged to actuate a follower 89 which, when raised by the cam, raises rod 86 against the tension of its spring 94. Said rod is held in its elevated position by a detent 92 engaging a shoulder 93 on said rod; the said detent being carried by the armature 91 of a release magnet 90; the circuit of which magnet is controlled by the contact device 18—19 operated by the universal shaft 14 of the key board. When a finger key 6 is depressed, selecting a particular combination of punches corresponding to the code character of that key, and raising corresponding stop pushers 83 so as to raise one of the stops 76, and closing clutch 54 and so causing shaft 44 to revolve, arm 85 is raised by the action of cam 88, follower 89 and rod 86, and as soon as said arm 85 clears the top of the stop pin 76 then in engagement with shoulder 84, said arm springs over the top of such pin 76, rod 86 being held in such elevated position by the detent lever 92. When the said finger key 6 is released and contact is closed between 18 and 19, release magnet 90 is energized, detent 92 is pulled back, rod 86 is forced down by its spring 94, carrying with it the restoring arm 85, and the pin 76, which has been holding the wheel 74 stationary, is depressed to normal position by said arm 85, wheel 74 then rotating until the other pin 76 just previously raised encounters shoulder 84.

Paper feed wheel 74 is rotated by a shaft 95 (Figs. 2, 4, 7, 11, 12, 14, and 17) driven by gearing 96 and a shaft 97, which shaft is driven through a jaw clutch 98 (Fig. 17) like jaw clutch 55 of the punching mechanism, but controlled by a finger key 99, said clutch being normally closed; and said clutch in turn is driven by a disk 100 (Figs. 1, 4, 6, 7, 15, 16 and 17) frictionally driven from a gear wheel 101 concentric therewith, and driven by gearing 57 from the main driving shaft of the motor 4. Disk 100 has a hub, as shown in Figs. 6 and 6^a, carrying a spiral spring 102 mounted within a flange 103 of gear wheel 101, and carrying a friction cushion 104 pressing against said flange. The construction is such that as gear wheel 101 revolves, the friction of its flange 103 against cushion 104, tends to drive disk 100 and will drive

said disk, if motion of the feed wheel be not arrested. The friction drive formed by flange 103 and cushion 104 and spring 102, permits motion of the feed wheel 74 to be arrested instantly, by the encounter of a stop pin 76 with stop shoulder 84, and causes said feed wheel to begin to rotate instantly when such stop pin 76 is knocked down clear of shoulder 84, as previously described.

0 The pushers 83, which set up the various pins 79, are operated from the tension wires 9 by bell crank levers 105 (Fig. 13). When one of said tension wires is depressed by a finger key, the corresponding bell crank 105 and pusher 83, are elevated, driving up one of pins 76.

To facilitate the introduction of the paper strip 21 through the paper feed mechanism I have provided the clutch 98, which when 20 opened permits the feed wheel 74 to be turned freely in either direction; and to operate said clutch I have provided a finger key 99, and a spring 107 engaging the same and tending to hold it in either the closed or 25 the open position of the clutch. To prevent unwinding of the spring 102 when the clutch 98 is opened, said key 99 is arranged to thrust a locking pin 108 into one of a series of 30 holes 109 in the rim of disk 100.

35 To keep the paper strip taut at all times while passing through the punching head and paper feed mechanism, I employ the friction wheels 23 and 24, above mentioned. One of these, 23, is positively driven, by a shaft 110, through a friction drive 111, but in a direction opposite to that of travel of the paper strip past it; the other wheel is a spring-pressed idler.

Operation.—The operation of the machine 40 is as follows: The paper strip having been fed into the machine from reel 20 by passing it around the various idlers 22, through the punch head 29 and around the feed wheel 74 (the clutch 98 being open) and thence 45 through the paper guide 25, and said clutch 98 having then been closed, when one of the finger keys 6 is depressed, certain of the tension wires 8 are depressed, thereby depressing the corresponding punch-actuating fingers 31, or series 32, or of both said 50 series, into position to operate their corresponding punches, and at the same time arm 63 on universal shaft 14 draws trip 65 down, raising stop 59 clear of lug 62 of clutch 55, 55 thus permitting said clutch to close. Gearing 57 being in rotation, shaft 44 immediately begins to revolve and cam 43 operates driver 41, moving all of the punch actuating fingers of both series forward, and thus fingers 60 which have been drawn down by their corresponding tension wires engage and drive forward the corresponding punches, driving them through the paper strip 21. The corresponding punches of the middle 65 row 27 are carried forward with the punches

of rows 26 and 28, thus punching the feed holes in the strip. The lug 62 of the punch mechanism clutch, encounters the opening cam 69, and is forced back thereby so as to open the clutch, said lug 62 springing, at the 70 conclusion of its movement, from cam 69 into engagement with stop 59 and thus arresting the motion of shaft 44. As soon as the end of the driver 41 reaches the drop on cam 43 it retreats, being forced backward by 75 the punch actuating fingers 31 and 32, which in turn are drawn backward by the universal bar 38 and spring 40. All of this occurs very quickly, shaft 44 being rotated at relatively 80 high speed, and occurs before the operator's finger can leave the finger key which has been depressed. When said finger key is released and allowed to rise, the contact device 18 and 19 (Fig. 5) of the circuit of restoring magnet 90 is closed, causing said magnet to 85 free the trip 92 (Fig. 8), arm 85 then descending and knocking down the stop pin 76 of the wheel 74 then in engagement with shoulder 84, thus permitting the feed wheel to revolve and feed the paper strip 21 onward. When 90 said finger key was first depressed it actuated one of wires 9 as well as certain of wires 8, and said wire, when depressed, raised a corresponding pusher 83, pushing up the appropriate stop pin 76. As feed wheel 74 95 now rotates, this second stop pin 76, encounters shoulder 84 again arresting the feed wheel, the paper strip having been fed a distance corresponding to the space occupied by the character just punched in the paper 100 strip.

In a machine of this sort, designed to be operated at high speed and to be operated continuously for hours at a time, it is of the utmost importance that the "touch" and 105 other qualities of the "action" of the machine which affect the rapidity of operation and the comfort of the operator, shall be the best possible. In particular, the touch must be light, the response to the depression of 110 the keys must be instantaneous, and the punching must be performed with exceeding rapidity, so that no matter how fleeting the duration of the pressure on the finger key, the punching shall have been completed before the circuit of magnet 90 is closed. It is highly important therefore, that the parts 115 actuated mechanically by the finger keys, shall be few, light, capable of rapid motion, and requiring very small movements and 120 very little power to operate them. These conditions are fulfilled in the mechanism illustrated and described. The detent device operated by the universal bar 12 and comprising the trip 65 and stop 59, is exceedingly sensitive, requiring only very slight 125 pressure and movement of the trip through a very short distance to release the clutch and permit the same to close. Aside from operating this trip, and the universal bar 12, 130

the finger keys have only to lower the corresponding punch actuating fingers 31 and 32 through a very short distance, and to raise one of the pushers 83 of the paper feed mechanism. All of these parts are very light, require to be moved through a very small distance by the finger keys, and are capable of being moved very rapidly with a very small expenditure of power. The parts to be moved by the finger keys being so light, and the distance through which they are to be moved being so small, and there being very little resistance to their movement, it is possible to pay particular attention to the touch of the machine, to make the range of movement of all of the finger keys practically the same, and the resistance to the movement of such keys nearly the same, to make the touch very light, and in general to embody in the machine those qualities of operation which make it possible to operate the machine constantly for long periods of time at a high rate of speed and with relatively little fatigue.

The punching mechanism, paper feed mechanism and certain other parts of this machine, embody features of the machine for the same purpose illustrated and described in my application for Letters Patent filed May 2nd, 1906, Serial Number 314,764, this machine being an improvement upon the machine shown in that application.

For carrying away the chips or punches, I have provided a chute arrangement in front of the die 30.

35 I intend the term "punches" as used in the following claims, to be generic to any device adapted to be actuated in the manner described for marking a paper strip or the like.

40 What I claim is:—

1. A machine of the class described, comprising in combination a series of punches, actuating fingers therefor corresponding in number to said punches and movable into and out of operative position with respect thereto, separate pivoted carriers for and adapted to move said fingers, a driver for said fingers, a plurality of character bars, and selecting members arranged transversely with respect to said character members and arranged to be actuated selectively thereby and mechanically connected to said carriers, each such carrier movable in substantially the plane of its said selecting member.

55 2. A machine of the class described comprising in combination a punch-head, punches therein, a keyboard comprising character levers, selecting members arranged beneath and transversely with respect to said character levers and arranged to be actuated selectively thereby, punch-actuating fingers, a driver therefor, and carriers for said fingers movable in a direction transverse to the di-

rection of motion of said punches and arranged to be so moved by said selecting members.

3. A machine of the class described comprising in combination a punch-head, punches therein, a keyboard comprising character levers, selecting members arranged beneath and transversely with respect to said character levers and arranged to be actuated selectively thereby, upright punch-actuating fingers, pivoted bell-crank carriers therefor, one arm of each bell-crank movable in a direction transverse to the direction of motion of said punches, the other connected to a corresponding one of said selecting members, and a driver for said fingers.

4. A machine of the class described comprising in combination a punch-head, punches therein, a keyboard arranged on a relatively lower level and comprising character levers, selecting members arranged beneath and transversely with respect to said character levers and arranged to be actuated selectively thereby, upwardly-projecting punch-actuating fingers, pivoted bell-crank carriers therefor, one arm of each bell-crank carrying the corresponding finger and the other arm connected to the corresponding selecting member, and a driver for said fingers.

5. A machine of the class described comprising in combination a punch-head, punches therein, a series of carriers movable in a direction transverse to the direction of motion of said punches, punch-actuating fingers mounted on said carriers, a driver for said fingers, a cam therefor, driving means for said cam, and a plurality of character members and selecting mechanism controlled thereby and controlling said carriers; said driving means also controlled by said character members.

6. A machine of the class described comprising in combination a punch-head, punches therein, a series of carriers movable in a direction transverse to the direction of motion of said punches, punch-actuating fingers mounted on said carriers, a driver for said fingers, a cam therefor, driving means for said cam, a plurality of character members, selecting mechanism mechanically controlled and operated thereby and mechanically connected to and operating said carriers, and means operated by the operation of said character members for controlling the operation of said driving means.

7. A machine of the class described comprising in combination a series of punches, arranged in two series, two series of actuating fingers, said fingers corresponding in number to said punches, the fingers of one series adapted also to actuate the fingers of the other series, said fingers all movable into and out of operative position with respect

to their respective punches, separate carriers for said fingers adapted to so move them, and a driver for said fingers.

8. A machine of the class described comprising in combination a series of punches, arranged in two series, two series of actuating fingers, said fingers corresponding in number to said punches, the fingers of one series adapted also to actuate the fingers of the other series, said fingers all movable into and out of operative position with respect to their respective punches, separate carriers for said fingers adapted to so move them, a driver for said fingers, and selecting means for operating said carriers.

9. A machine of the class described comprising in combination a series of punches, arranged in two series, two series of actuating fingers, said fingers corresponding in number to said punches, the fingers of one series adapted also to actuate the fingers of the other series, said fingers all movable into and out of operative position with respect to their respective punches, separate carriers for said fingers adapted to so move them, a driver for said fingers, and selecting means comprising a keyboard having finger keys for operating said carriers.

10. A machine of the class described, comprising in combination a plurality of punches arranged in two series, two corresponding series of actuating fingers pivotally mounted, one behind the other, means for moving one of said series of fingers together in a body and through that series the other as well, to operate said punches, and means for moving said fingers into and out of operative position with respect to their corresponding punches, comprising a plurality of character members and selecting means operated thereby.

11. A machine of the class described comprising in combination a series of punches, actuating fingers therefor corresponding in number to said punches, and separate carriers for said fingers, adapted to move same into and out of operative position with respect to their respective punches, said fingers normally out of such operative position, selecting means for selecting and actuating appropriate carriers, comprising a keyboard having finger keys, tension wires arranged transversely across said finger keys and connected mechanically to said carriers, said keys arranged to operate said wires selectively and mechanically, and a driver for said fingers.

12. A machine of the class described comprising in combination punches arranged in two series, the two corresponding series of actuating fingers, one arranged in rear of the other with the fingers of one series in position to be advanced by the corresponding fingers of the other series, means for moving any finger or fingers of either or both series

into or out of operative position with respect to the corresponding punch or punches, and the driver for said fingers.

13. A perforating machine comprising in combination punches arranged in two series, two corresponding series of headed actuating fingers, one series of such fingers comprising also heads for operating corresponding fingers of the other series, means for moving any finger or fingers of either or both series into or out of operative position with respect to the corresponding punch or punches, and the driver for said fingers.

14. A machine of the class described comprising in combination a plurality of character members, punching mechanism comprising a plurality of punches, punch-operating fingers corresponding to said punches and movable to operate the same and also movable into and out of operative position with respect thereto, carriers for said fingers, pivoted thereto, means for actuating said fingers to actuate said punches comprising a clutch controlled by said character members, and means for moving said fingers into and out of operative position with respect to their corresponding punches, comprising selecting means operated by said character members and connected to said carriers.

15. A machine of the class described comprising in combination a series of punches, a series of corresponding punch-actuating fingers, a series of carriers to which said fingers are connected, tension wires connected to said carriers, finger keys having means for operating selected ones of said tension wires, and a driver for said fingers.

16. A machine of the class described comprising in combination punching mechanism, finger keys and means controlled thereby controlling said punching mechanism, feed mechanism comprising a rotary feeding member, stops carried thereby, a series of pushers therefor arranged substantially in line with said stops, operating means for each of said pushers comprising pivoted levers, tension wires secured thereto and extending transversely across said keys, each such key provided with means for operating mechanically a corresponding one of said wires, and means for restoring said stops.

17. In a machine of the class described, feeding mechanism comprising in combination a rotary carrier, adjustable stops carried thereby, means controllable by finger keys for setting up said stops, means for engaging said stops to arrest the carrier, a restoring member, spring-actuated in one direction, power mechanism for actuating same in the opposite direction, and a detent for holding and releasing said member.

18. In a machine of the class described, feeding mechanism comprising in combination a rotary carrier, adjustable stops car-

ried thereby, means controllable by finger keys for setting up said stops, means for engaging said stops to arrest the carrier, a restoring member, spring-actuated in one direction, power mechanism for actuating same in the opposite direction, and a magnet and detent mechanism operated thereby for holding and releasing said member.

19. A machine of the class described comprising in combination punching mechanism, power mechanism for driving the same, finger keys for releasing said power mechanism and controlling the operation of said punching mechanism, feeding mechanism comprising a power driven feed member, adjustable stops carried thereby, means controlled by said finger keys for setting up said stops, a restoring member, spring actuated in one direction, power driven means for actuating same in the opposite direction, a detent for holding said restoring member in set position, and means actuated by said finger keys for releasing said detent.

20. A machine of the class described comprising in combination punching mechanism, power mechanism for driving the same, finger keys for releasing said power mechanism and controlling the operation of said punching mechanism, feeding mechanism comprising a power driven feed member, adjustable stops carried thereby, means controlled by said finger keys for setting up said stops, a restoring member, spring actuated in one direction, power driven means for actuating same in the opposite direction, a detent for holding said restoring member in set position, a magnet for releasing said detent, and contact means controlled by said keys for controlling said magnet.

21. A machine of the class described comprising in combination a keyboard, driving mechanism, punching mechanism and feed mechanism arranged to be driven thereby, and located at the side of said keyboard, selecting controlling mechanism for said punching and feeding mechanisms, including actuating devices mechanically connected to parts of said punching and feeding mechanisms extending transversely across the keyboard and arranged to be operated selectively by the keys thereof, said punching mechanism comprising a plurality of punch-actuating fingers adapted to move into and out of operative position with respect to corresponding punches, and a driver for said fingers.

22. A machine of the class described comprising in combination a keyboard, driving mechanism, punching mechanism and feed mechanism arranged to be driven thereby, and located at the side of said keyboard, said feed mechanism comprising a power driven feeding member having adjustable stops, and push bars for adjusting said stops arranged substantially in line therewith, and

selecting controlling mechanism for said punching and feeding mechanisms, including actuating devices extending transversely across the keyboard and arranged to be operated selectively by the keys thereof, and mechanically connected to parts of said punching mechanism and to said push bars of said feed mechanism.

23. A machine of the class described comprising in combination a keyboard, driving mechanism, punching mechanism, feeding mechanism located at the side of said keyboard, and selecting controlling mechanism for said feeding mechanism comprising actuating devices extending transversely across said keyboard and arranged to be selectively operated by the keys thereof, said feeding mechanism comprising a movable carrier, adjustable stops carried thereby, pushers therefor located substantially in line therewith, and bell cranks connected to said pushers and likewise connected to said transverse actuating devices.

24. A machine of the class described comprising in combination a keyboard, driving mechanism, and punching mechanism located at one side of said keyboard and arranged to be driven by said power mechanism, and comprising punches, punch operating fingers, pivoted levers carrying the same, and a driver, and controlling means for said punching mechanism including selecting means comprising operating members arranged transversely of said keyboard and selectively operated by the keys thereof, and connected to said pivoted levers.

25. A machine of the class described comprising in combination a keyboard, a main driving shaft, punching mechanism and feeding mechanism, and separate driving shafts therefor, and means operatively connecting said shafts to said main driving shaft, such connecting means of the punch mechanism shaft comprising a clutch controlled by finger keys of the keyboard, such driving mechanism of the feed mechanism shaft comprising yielding driving means, within a gear wheel of said driving mechanism.

26. A machine of the class described comprising in combination a keyboard, a main driving shaft, punching mechanism and feeding mechanism, and separate driving shafts therefor, and means operatively connecting said shafts to said main driving shaft, such connecting means of the punch mechanism shaft comprising a clutch controlled by finger keys of the keyboard, such driving mechanism of the feed mechanism shaft comprising a friction drive within a gear wheel of said driving mechanism.

27. A machine of the class described comprising in combination a keyboard, a main driving shaft, punching mechanism and feeding mechanism, and separate driving shafts therefor, and means operatively con-

- necting said shafts to said main driving shaft, such connecting means of the punch mechanism shaft comprising a clutch controlled by finger keys of the keyboard, such driving mechanism of the feed mechanism shaft comprising yielding driving means within a gear wheel of said driving means, a clutch, and means which locks said yielding driving means when said clutch is open.
28. A machine of the class described comprising in combination punching mechanism and feeding mechanism, a main driving shaft, a gear driven thereby, separate driving shafts for said punching mechanism and feeding mechanism on opposite sides of said gear, and means for driving said shafts from said gear wheel, such driving means for the feed mechanism shaft comprising two members, a wheel and a locking disk, one such member provided with a friction ring, and the other with a spring actuated friction device engaging said ring, a clutch interposed between said locking disk and the feeding mechanism, and locking means actuated upon the opening of said clutch, to lock said disk.
29. A machine of the class described comprising in combination feeding mechanism, punching mechanism, paper guiding means for guiding a paper strip through said punching mechanism and feed mechanism successively, and positively driven retarding means frictionally engaging said strip in rear of said punching mechanism and tending to draw said strip back.
30. A machine of the class described, comprising in combination a plurality of character members, punching mechanism, a power member, means for transmitting power therefrom to said punching mechanism comprising a clutch including means tending normally to close it, a detent normally holding said clutch open, a universal bar actuated by said character members, a trip actuated by said bar for actuating said detent, and means for disengaging said trip from the detent after each operation of the detent by said trip.
31. A machine of the class described comprising in combination punching and paper feed mechanism, character members and means operated thereby controlling said mechanisms, a power member and means operated thereby for transmitting motion to mechanism of said machine comprising an automatically closing clutch, a pivoted detent normally holding said clutch open, a universal member actuated by the several character members and means actuated thereby for operating said detent to release the clutch comprising a sliding trip movable in the direction of movement of said detent and normally engaging said detent, and means for disengaging such trip from a detent during such movement of the former.
32. A machine of the class described comprising in combination punching and paper feed mechanism, character members and means operated thereby controlling said mechanisms, a power member and means operated thereby for transmitting motion to mechanism of said machine comprising an automatically closing clutch, a pivoted detent normally holding said clutch open, a universal member actuated by the several character members and means actuated thereby for operating said detent to release the clutch comprising a sliding trip movable in the direction of movement of said detent and normally engaging said detent, and means for supporting and guiding such cam surface for such purpose.
33. A machine of the class described comprising in combination two rows of punches, means for actuating independently the punches of one of said rows, each punch of such row provided with means engaging a corresponding punch of the other row, and also a punch of such row next beyond, whereby any punch of the first row when operated operates two punches of the second row, said second row punches arranged in pairs, one punch of each such pair provided with means engaging the other punch of such pair to cause them to move together, such second punch of each pair nevertheless free to move independently, a third row of punches and means for actuating same, the several punches of such third row each provided with means engaging corresponding punches of the second row to cause same to operate therewith, and means for supporting and guiding said punches.
34. A machine of the class described comprising in combination a plurality of punches arranged in three parallel and superposed rows, the middle row of punches arranged in pairs and provided with engaging means whereby one punch of such pair when operated carries with it the other punch of such pair, such second punch of each such pair nevertheless free to move independently, each punch of one of the outside rows provided with means engaging the pair of punches next beneath and causing both such punches to operate, each punch of the other outside series provided with means engaging the middle row punch next above and the middle row punch next beyond, whereby both such middle row punches are operated each time the punch so engaging is operated, supporting and guiding means for said rows of punches and means for actuating the punches of the two outside rows.
35. A machine of the class described comprising in combination a plurality of punches arranged in three parallel superposed rows, means for supporting and guiding said

punches, operating means for the two outside rows, the punches of said rows provided with means for operating corresponding punches of the middle row, spring operated universal returning members for the outside rows of punches, and means for returning the punches of the middle row.

36. A machine of the class described comprising in combination a plurality of punches arranged in three parallel superposed rows, means for supporting and guiding said punches, operating means for the two outside rows, the punches of said rows provided

with means for operating corresponding punches of the middle row, means for returning the punches of the two outside rows, spring actuated pivoted universal bars normally engaging all of such punches and returning means for the middle row punches. 15

In testimony whereof I affix my signature, in the presence of two witnesses.

JOHN C. BARCLAY.
